UNITED STATES PATENT OFFICE.

CHARLES W. DAKE, OF GRAND RAPIDS, MICHIGAN.

ELASTIC-FLUID TURBINE.

No. 828,934.

Specification of Letters Patent.

Patented Aug. 21, 1906.

Application filed November 29, 1905. Serial No. 289,660.

To all whom it may concern:

Be it known that I, CHARLES W. DAKE, a citizen of the United States, residing at Grand Rapids, county of Kent, and State of Michigan, have invented certain new and useful Improvements in Elastic-Fluid Turbines, of which the following is a specification.

This invention relates to improvements in elastic-fluid turbine-engines, and more particularly to an important modification of the structure appearing in my application concurrent herewith, this change relating to the particular formation and relation of the guide-passages in the nozzle and guide-passage block.

This improvement has for its object to provide means for more readily recurring and returning the flow of steam in the guide-passages as it passes from the buckets on one side of the block to the buckets on the other side.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

Figure 1 is a detail transverse sectional view, full size, through the buckets, guide-blocks, casing, and casing-cover, taken on a line corresponding to irregular line $z z$ of Fig. 3. Fig. 2 is a similar detail sectional view, the casing-cover being omitted and only a portion of the casing being shown, taken on a line corresponding to line $x x$ of Fig. 3; and Fig. 3 is a detail side elevation view of one of the nozzle and guide-passage blocks in position in the casing, the row of buckets 4 being removed to facilitate observation. The sectional views are taken looking toward the right of Fig. 3.

Similar numerals of reference refer to similar parts throughout the several views.

Referring to the numbered parts of the drawings, the casing 1 is provided with an inlet-passage 7, leading to an annular chamber 8, which delivers through passages 9 and 10 to a nozzle 11. Buckets 12 and 14, formed in segments 4 and 5, are retained in the web 6 of the wheel, according to the plan claimed and described by me in another concurrent application.

The nozzle 11 delivers into buckets 12 and thence, traveling through the buckets 12, enters a passage 13 near the periphery of the turbine-wheel. This passage 13 extends transversely, inwardly, and forwardly from the bucket 12, recurving upon itself to deliver the steam therefrom in substantially the same direction from which it was received and delivering it to the inner side of buckets 14, whence it passes through the buckets, developing its force by impact and by reaction, whence it passes outwardly from the outer side of the buckets into the fluid-passage 15, which passage curves upon itself and extends inwardly, forwardly, and transversely to the inner line of the buckets at a point in advance of the nozzle 11. Thence it delivers into the inner side of the buckets again, reacting outwardly at the outer side, and enters an exit-passage 16 and 17, from whence it passes to an annular exhaust-chamber 18 in the casing 1 and thence out at the exhaust.

The angle of each of these passages 13 and 15 at the point of exit of the steam from the buckets is substantially an acute angle of twenty degrees thereto, and where the passage passes through the block 3 and delivers to the opposite bucket it delivers the steam thereto at an angle of substantially twenty degrees, so that the receiving and discharge ends of these passages stand substantially at an angle to each other in the plane of their action of about forty degrees, and they are curved upon themselves, so that in their tangential action upon the turbine-wheel the current of the steam is substantially reversed or turned upon itself, so that its impact upon the buckets tends to drive the wheels always in the same direction. Extending the passage from the outer side to the inner side of the buckets in this way is a great convenience in formation, as there is plenty of room for the steam to turn without being unduly confined, the force of the steam not being retarded by too sharp an angle in the guiding-passage.

Steam has been mentioned as the actuating fluid, but it is desired to remark that any elastic fluid under pressure will serve the purpose, and I do not intend to be confined to steam merely in this turbine.

The guide-block 3 is secured to the casing 1 by suitable screws, as shown, and is properly curved to fit in between the segments 4 and 5.

of the turbine-wheel. The annular exhaust-passage 18 delivers out from the engine at any convenient place and receives the steam from the exit-passages 17 at intervals around the wheel, as many of the blocks 3 being made use of as the size of the turbine and power to be developed requires. The exit-passage in the case 17 receives the steam from the exhaust-passage 16 in the nozzle 10 and guide passage block, such passage receiving the steam directly from the buckets of the turbine.

It is desired to remark in the matter of modification that the block 3 of course might be made integral with the other parts of the structure, or, for that matter, it might be further divided into separate pieces, which might contain the passages to which I have referred, or such passages might be formed 20 by grooves between the parts. I merely mention this so that when I refer to "segment-block" it will be understood that it refers to the part generally and not to a specific integral block.

Having thus described my invention, what I claim as new, and desire to secure by Letters Patent, is—

1. In an elastic-fluid turbine, the combination with a suitable casing, of the turbine-wheel, with bucket-segments 4 and 5 on opposite sides thereof, with buckets formed therein suitably curved to receive impulse from the impact of the fluid and the reaction therefrom; a guide-block with a suitable passage therethrough terminating in a nozzle delivering into the inner sides of said buckets; and recurved guide-passages from the outer periphery of said buckets, extending inwardly, forwardly and transversely, to guide the elastic fluid from the buckets of one side to the buckets of the opposite side, and a second recurved guide-passage leading from the outer part of the second group of buckets inwardly, forwardly and transversely through the said guide-block to deliver into the inner part of the opposite group of buckets; and an exit-passage through said guide-block from the outer part of said buckets connecting with a suitable exit-passage to the exhaust, coacting for the purpose specified.

2. In an elastic-fluid turbine, the combination with a suitable casing, of the turbine-wheel, with bucket-segments 4 and 5 on opposite sides thereof, with buckets formed therein suitably curved to receive impulse from the impact of the fluid and the reaction therefrom; a guide-block with a suitable passage therethrough terminating in a nozzle delivering into the inner sides of said buckets; and recurved guide-passages from the outer periphery of said buckets, extending inwardly, forwardly and transversely, to guide the elastic fluid from the buckets of one side to the buckets of the opposite side; and an exit-passage through said guide-block from

the outer part of said buckets connecting with a suitable exit-passage to the exhaust, coacting for the purpose specified.

3. In an elastic-fluid turbine, the combination in a suitable casing, of a turbine-wheel 70 having lines of buckets facing each other from the opposite sides of said disk, the buckets being formed in the said wheel and facing each other and curved to receive impulses from the impact of the fluid and the reaction 75 therefrom; a guide-block with suitable passages therethrough, terminating in a nozzle delivering into the inner sides of the said buckets; recurved guide-passages from the outer periphery of said buckets extending inwardly, forwardly and transversely to guide 80 the elastic fluid from the buckets of one side to the buckets of the opposite side; a second recurved guide-passage leading from the outer part of the second group of buckets inwardly, forwardly and transversely through 85 the said guide-block, to deliver to the inner part of the opposite group of buckets; and an exit-passage through said guide-block from the outer part of said blocks, connecting with 90 a suitable exit-passage to the exhaust, coacting for the purpose specified.

4. In an elastic-fluid turbine, the combination in a suitable casing, of a turbine-wheel 95 having lines of buckets facing each other from the opposite sides of said disk, the buckets being formed in the said wheel and facing each other and curved to receive impulses from the impact of the fluid and the reaction 100 therefrom; a guide-block with suitable passages therethrough, terminating in a nozzle delivering into the inner sides of said buckets; recurved guide-passages from the outer periphery of said buckets extending inwardly, forwardly and transversely to guide 105 the elastic fluid from the buckets of one side to the buckets of the opposite side; and an exit-passage through said guide-block from the outer part of said blocks, connecting with 110 a suitable exit-passage to the exhaust, coacting for the purpose specified.

5. In an elastic-fluid turbine, the combination of a suitable turbine-wheel having oppositely-faced rows of buckets curved and formed to drive in the same direction; a nozzle delivering to one edge of one of such rows of buckets; a guide-passage delivering from the opposite edge of the said row of buckets transversely and diagonally forward to the opposite side of the opposite row of buckets, 115 coacting as specified.

6. In an elastic-fluid turbine, the combination of a suitable turbine-wheel having oppositely-faced rows of buckets curved and formed to drive in the same direction; a nozzle delivering to one edge of one of such rows of buckets; and recurved diagonal guide-passages between the oppositely-faced buckets, as specified.

7. In an elastic-fluid turbine, the combina-

- tion of a turbine-wheel with lines of oppositely-facing buckets formed to drive the wheel in the same direction; a guide-block having passages and nozzles arranged between the said oppositely-facing buckets, the nozzle delivering to one of said buckets; and a recurved guide-passage connecting the opposite side of said row of buckets, diagonally and transversely, with the oppositely-faced row of buckets, coacting for the purpose specified. 8. In a turbine-engine, the combination of the casing 1, with its cover 2, inlet-passage 7, with the annular chamber 8, guide-passage 9 and 10 reaching therefrom; the disk 6; oppositely-faced bucket-segments 4 and 5 with buckets 12 and 14 formed therein; the nozzle 11, delivering to the said buckets; the transverse, diagonally-recurved guide-passages 13 and 15 through the guide-block; and the exit-passage, coacting for the purpose specified. 9. In a turbine-engine, the disk 6; oppositely-faced bucket-segments 4 and 5 with buckets 12 and 14 formed therein; the nozzle 11, delivering to the said buckets; the transverse, diagonally-recurved guide-passages 13 and 15 through the guide-block; and the exit-passage, coacting for the purpose specified. 10. In witness whereof I have hereunto set my hand and seal in the presence of two witnesses.
